UNITED STATES PATENT OFFICE.

NELSON A. LOCKWOOD, OF OGDEN, UTAH.

PLUG-VALVE INSTALLATION FOR TANKS.

Application filed March 15, 1920. Serial No. 365,959.

To all whom it may concern:

Be it known that I, NELSON A. LOCKWOOD, a citizen of the United States, residing at Ogden, in the county of Weber and State 5 of Utah, have invented certain new and useful Improvements in Plug-Valve Installations for Tanks; and I do hereby declare the following to be a full, clear, and exact description of the invention, such as will 10 enable others skilled in the art to which it appertains to make and use the same.

This invention embodies improvements in plug valve installations for tanks, and has been more particularly devised with 15 reference to the steel containers or carbonation tanks employed in the step of precipitating lime salts from saccharine juices in the manufacture of sugar, although in actual applications it may also be found to 20 be very expedient in other spheres of usefulness.

Heretofore, it has been the common custom to mount these plug valvular elements, for stoppering the discharge outlet for the 25 contained sugar juices in carbonation tanks, in association with a stuffing box arrangement and operated by bell crank levers and connections, all of which has proven to be very objectionable in actual practice, for 30 various reasons, and an efficiently satisfactory method of installation has long been sought for to overcome objections heretofore met with.

The primary object of the instant invention, therefore, is to overcome former disadvantageous features, in the attainment of the ends desired, by the provision of a novel, simple and effective manner of installation, which will not only enable the plug valve 40 to be actuated with a direct and positive longitudinal thrust but which will also permit of a plug valve, with its stem located interiorly of a substantially closed carbonation tank, to be operated positively from a 45 conveniently accessible position exteriorly thereof.

These and other objects and advantages, however, will be so clearly apparent, as incidental to the following disclosure, that 50 it would only be undesirable surplusage to further enlarge upon the same initially, and with these prefacing remarks reference will now be immediately had to the accompanying drawings, illustrating a practical embodiment of the improvements, in which 55 drawings—

Figure 1 is a fragmentary longitudinal sectional view, of the lower portion of a carbonation tank, taken in a plane along the line 1—1 of Fig. 3, and illustrating my 60 improved manner of installing and operating its plug foot valve; Figure 2 is a local sectional view, illustrating on an enlarged scale the plug valve seating; and Figure 3 is a fragmentary cross-sectional view on 65 the line 3—3 of Fig. 1.

5 designates the lower peripheral wall of a tank having a sloping bottom 6, seated on an internal annular angle-iron base rim 7, the peripheral web of which latter is 70 riveted to the wall of the tank, as at 8, and its horizontal web being riveted to the bottom 6, as at 9.

Towards its lowermost position, the bottom 6 is provided with an outlet orifice 10 75 for the discharge of the tank's contents, as desired, under control of a foot valve.

The foot valve, as will hereinafter appear, operates as a plug closure for an outlet connection 11, having a downwardly 80 converging conical seating bore 12 and the lower and upper coupling annular flanges 13 and 14, respectively.

The top flange 14 fits up against the underneath face of an annular washer 15, 85 which underneath face is caused to be disposed horizontally by virtue of the washer being beveled on its upper face to correspond with the inclination of the bottom 6. The washer has a central aperture 16, of 90 conical formation to register congruently as a continuation of the conical bore 12 and in open communication with the tank through the outlet orifice 10, the flange 14 of the coupling valve seat being securely fitted to the 95 bottom of the tank through the interposed washer 15 and suitable stud bolts or rivets 17, all as shown in detail at Fig. 2.

18 indicates an inwardly projecting bracket arm having its outer end riveted to 100 the inside of the tank, as at 19, and its inner end terminating with a thickened portion 20 having a squared, or other non-cylindrical, bearing aperture 21 disposed in axial alignment with the conical bore 12. 105

The peripheral or vertical wall of the 110 standing tank is cut away, at a suitable height above the outlet 10, to provide an enlarged or hand hole 22 that is encompassed by a housing 23, which latter opens outwardly through said hand hole, in substantially unobstructed disposition, and is

2 laterally projected inwardly over the tank outlet, the said housing being fluid-tight, with reference to the interior of the tank, and being formed by the vertical rear wall 5 24, the vertical side walls 25 having circumferentially turned flange terminals 26, a bottom wall 27 having the flange terminal 28, and an upwardly inclined top wall 29 having the flange terminal 30, all of the said 10 terminal flanges being fastened pressure-tight against the inside face of the tank's wall by series of rivets 31.

The bottom wall 27 has an upper bearing aperture 32, in axial line with the lower bearing aperture 21, and securely mounted thereover is a valve stem bonnet, comprising a base 34 supporting an inverted U-shaped member 33, centrally apertured to freely journal an interiorly threaded cylindrical shank 36, provided at its lower end with a collar flange 37 and at its upper end with a hand wheel 38.

The shank 36 is in reality a reduced continuation of the enlarged interiorly threaded hub of the hand wheel 38, the bottom face of which is revolvably seated on a flattened face provided at the top of the U-shaped bonnet section.

39 is an elongated valve stem, extending 30 through the bearing aperture 32 in association with a gland packing arrangement 35, with its upper end terminating within the housing 23 and being threaded, as at 40, for operative engagement with the internal 35 threads of the shank 36 and wheel hub.

Towards its lower end the valve stem is squared off at 41, passing through the lower bearing aperture 21 in reciprocating but non-rotatable relation, and at its extreme 40 lower end it is formed cylindrical, as at 42, terminating in a cylindrical abutment disc 43.

The lower end 42 thereof passes freely 45 through a centrally bored nut 44, which is externally threaded to screw into a threaded socket 45 of a conical plug valve 46, the lower portion of the socket being smooth bored, as at 47, to receive the abutment disc 43 underneath the nut 44, thus permitting of 50 a rotary seating play of the conical foot valve 46, regardless of its reciprocatory actuation by its non-rotatable stem.

From the foregoing complete description, it is believed to be apparent, without a 55 further detailed statement of operations, that upon turning the hand wheel in opposite directions, the plug valve alternately will be elevated with a direct rigid pull, to open the discharge outlet, and reversely actuated with a direct positive seating thrust, to close the discharge outlet, whereby, with 60 its stem reciprocating within a substantially pressure-tight tank, the valvular element may be facilely controlled by the hand wheel 65 exteriorly thereof in a conveniently housed

position located inside the areal limits of the tank, thus not only avoiding objectionable exteriorly projecting parts but also entirely eliminating the need for a stuffing box 70 for the foot valve as well as all bell crank levers and connections.

It is to be understood that I do not necessarily limit myself to the exact details shown and described, excepting as they may come within the terms of the ensuing claims, 75 or when fairly interpreted in the light of the specification and understood equivalents if necessary but what I do claim, as new and patentable, is:—

1. The combination of a tank, having a 80 discharge outlet with a valve and seat therefor, an inset housing that provides an open front encompassing an enlarged and substantially unobstructed opening formed in a wall of said tank, the said housing being 85 projected laterally within said tank over said discharge outlet and being substantially fluid-tight with reference to the interior of said tank, a valve stem in said tank, having one end extending in fluid-tight relation 90 through a wall of said housing, and suitably terminating within said housing, while its other end is connected with said valve, and means associated with said extended end for facilely actuating said valve stem from a 95 convenient position within said inset housing.

2. The combination of an upstanding tank, having a discharge outlet at its bottom with a valve and seat therefor, an inset housing 100 that provides an open front encompassing an enlarged and substantially unobstructed opening formed in the peripheral wall of said tank, the said housing being projected from said peripheral wall laterally within 105 said tank over said bottom and discharge outlet and being substantially fluid-tight with reference to the interior of said tank, an elongated rectilinearly operating valve stem, disposed in said tank, having its upper 110 end extending in fluid-tight relation through the bottom wall of said housing, and suitably terminating within said housing, while its lower end is connected with said valve, and means associated with the upper end of said valve stem for facilely actuating the latter 115 from a convenient position within said inset housing.

3. The combination of an upstanding tank, having a discharge outlet at its bottom 120 with a plug valve and seat therefor, an inset housing that provides an open front encompassing an enlarged and substantially unobstructed opening formed in the peripheral wall of said tank, the said housing being 125 projected from said peripheral wall laterally within said tank over said bottom and discharge outlet and being substantially fluid-tight with reference to the interior of said tank, an elongated rectilinearly operating 130

non-rotatable valve stem, disposed in said tank, having its upper end extending in fluid-tight relation through the bottom wall of said housing, and suitably terminating 5 within said housing, while its lower end is so connected with said plug valve as to permit of a rotary play of the latter thereon, and means associated with the upper end of said valve stem for facilely reciprocating 10 said valve stem and its plug valve from a convenient position within said inset housing.

4. The combination with a tank having a discharge outlet with an associated plug 15 valve and seat therefor; of a housing providing an open front encompassing an enlarged hand-hole opening formed in a wall of said tank, the said housing being projected within the areal confines of said tank 20 in line with said discharge outlet; a valve stem disposed in said tank and non-rotatably mounted to reciprocate therein, with one end so connected with said plug valve as to permit of a rotary play of the latter thereon and 25 with its other end screwthreaded and extended into said housing; a valve stem bonnet suitably mounted within said housing to straddle said valve stem and having an enlarged aperture for the passage of the stem's 30 threaded end; and a hand wheel having a barrel shank hub extension freely journaled in said bonnet aperture and being internally threaded for operative association with the threaded end of said valve stem, to reciprocate the latter and its plug valve, substantially as described.

In testimony whereof, I affix my signature.

NELSON A. LOCKWOOD.
